[57] CLAIM

The ornamental design for barbecue skewer handle, as shown and described.

DESCRIPTION

FIG. 1 is a lower left frontal view in perspective of a barbecue skewer handle embodying my new design with the skewer portion shown in phantom lines;

FIG. 2 is a lower left frontal view in perspective of the barbecue skewer handle shown in FIG. 1;

FIG. 3 is a front elevational view thereof which is identical to the rear elevational view thereof;

FIG. 4 is a right side elevational view thereof which is identical to a left side elevational view thereof;

FIG. 5 is a top plan view thereof;

FIG. 6 is a bottom plan view thereof;

FIG. 7 is a lower left frontal view in perspective of a second modified form of a barbecue skewer handle embodying my new design;

FIG. 8 is a frontal elevational view of the barbecue skewer handle shown in FIG. 7 which is identical to the rear elevational view thereof;

FIG. 9 is a right side elevational view of the barbecue skewer handle shown in FIG. 7 which is identical to the left side elevational view thereof;

FIG. 10 is a top plan view of the barbecue skewer handle of FIG. 7;

FIG. 11 is a bottom plan view of the barbecue skewer handle of FIG. 7;

FIG. 12 is a lower left frontal view in perspective of a third modified form of a barbecue skewer handle embodying my new design;

FIG. 13 is a front elevational view of the barbecue skewer handle shown in FIG. 12 which is identical to the rear elevational view thereof;

FIG. 14 is a right side elevational view of the barbecue skewer handle shown in FIG. 12 which is identical to the left side elevational view thereof;

FIG. 15 is a top plan view of the barbecue skewer handle of FIG. 12;

FIG. 16 is a bottom plan view of the barbecue skewer handle of FIG. 12;

FIG. 17 is a lower left frontal view in perspective of a fourth modified form of a barbecue skewer handle embodying my new design;

FIG. 18 is a front elevational view of the barbecue skewer handle shown in FIG. 17 which is identical to the rear elevational view thereof;

FIG. 19 is a right side elevational view of the barbecue skewer handle shown in FIG. 17 which is identical to the left side elevational view thereof;

FIG. 20 is a top plan view of the barbecue skewer handle of FIG. 17; and,

FIG. 21 is a bottom plan view of the barbecue skewer handle of FIG. 17.

The broken lines are for illustrative purposes only and form no part of the claimed design.
